UNITED STATES PATENT OFFICE

103,741

DESIGN FOR A WHEEL

James W. Pattison, Detroit, Mich., assignor to
Kelsey-Hayes Wheel Company, Detroit, Mich.,
a corporation of Delaware

Application August 17, 1936, Serial No. 64,449

Term of patent 14 years

To all whom it may concern:

Be it known that I, James W. Pattison, a citizen of the United States of America, residing at Detroit, in the county of Wayne and State of Michigan, have invented a certain new, original, and ornamental Design for a Wheel, of which the following is a specification, reference being had therein to the accompanying drawing forming a part thereof, in which Figure 1 is a perspective view of the wheel body; Figure 2 is a fragmentary front elevation of the wheel; and Figure 3 is an axial section therethrough.

The present design comprises as the principal and dominating features thereof that portion of the wheel body shown in full lines made convex with two annular concentric beads and presenting substantially the appearance from the front of a solid body; and the radially outer bead having substantially radial openings therethrough in the zone adjacent the rim.

I claim:

The ornamental design for a wheel, substantially as shown and described.

JAMES W. PATTISON.
